GRAPPLE

William T. Fulton, Tacoma, Wash.

Application June 6, 1945, Serial No. 597,887

3 Claims. (Cl. 294—28)

1

The present invention relates to a grapple and, more particularly, to a bottle or jar grasping and lifting tool, useful to housewives, canners and bottlers.

It is my experience that, of the many lifters and carriers to be found in the prior art, the majority are impractical to make or use. A prime criticism with these prior devices is that the grip obtained upon the object to be handled is in direct proportion to the pressure applied by the person using the tool, since these devices usually have a pair of relatively movable jaws that are maintained in the closed position by manual force alone.

It is an important object of my invention to provide a grapple in which the jaws open merely by swinging one of the jaw-carrying members about the axis of the handle, and which close and are retained by gravity when the jaw-carrying handle member is permitted to swing downward about its handle axis.

Another important object of the invention is to provide a device of the nature described in which the jaws are maintained about the object being grasped by the weight of the object and without any mechanical locking together of the jaws or the employment of other means of retaining them together, manual or otherwise.

A further object of the invention resides in the provision of a device of the nature described which may be manufactured simply and assembled without difficulty, and which is strong and durable and easy to manipulate.

The foregoing objects and others ancillary thereto, I prefer to accomplish as follows:

According to a preferred form of my invention, I provide a first and a second pair of arms, each of which pair is joined together at the lower ends by a curved jaw portion and which pairs are arranged together so that the jaw portions are disposed in opposition to each other, and so that an arm of each pair lies adjacent an arm of the other pair. The arms of the first pair are substantially longer than the arms of the second pair, and are bent or shaped intermediate their ends at a distance above the jaw slightly less than the length of the arms of the second pair to form an obtuse angle on that side of the arms away from the jaw. Each of the first pair of arms has a pivotal connection, adjacent this bend, with the upper ends of the second pair of arms so that the jaws may be swung apart or closed together. The first pair of arms is joined at the upper end to form a handle, by which the grapple may be manipulated to open or close the jaws. In the

2

closed position, the second pair of arms tend to pass the first pair of arms to provide an overlapping relationship between the jaws. When the jaws are closed about the neck of a bottle or jar, a lift applied to the grapple through the handle will carry with it the object engaged and the weight of the object will tend to keep the jaws closed. Disengagement of the grapple from the object is obtained merely by swinging the first pair of arms about the axis of the handle so that the handle tends to approach the jaw of the second pair of arms, and the object will be disengaged, whether setting upon a support or in mid-air, either of which situations may be desirable under certain circumstances.

In the preferred form of my invention, I fabricate the same from wire, but it will be obvious to those skilled in the art that the same may be satisfactorily formed and equally useful when 20 strap or cast material is used.

The novel features that I consider characteristic of my invention are set forth with particularity in the appended claims. The invention itself, however, both as to its organization and its 25 method of operation, together with additional objects and advantages thereof, will best be understood from the following description of a specific embodiment when read in connection with the accompanying drawings, in which:

Fig. 1 is a perspective view of my grapple;

Fig. 2 is a view in side elevation of my grapple suggested by the dotted line position of the jaws when open; and

Fig. 3 is a view in elevation taken in a plane 35 at right angles to that shown in Fig. 2.

A grapple, to overcome the defects hereinabove enumerated, must have at least two totally distinct characteristics: It must be capable of rapid manipulation to open as well as close the jaws 40 about an object to be handled; and it must also provide a firm grip, disengageable at the will of the operator, but not unintentionally by reason of any normal movement imparted during use.

Accordingly, a preferred embodiment of my 45 invention, referring to the figures of the drawing, is constituted by a first member comprising a handle 10, having depending therefrom arms. Each arm includes upper portion 12 and lower portion 14, and are arranged together to form 50 an obtuse angle directed toward one side of the handle. The lower ends of the jaws are joined by means of a bow-shaped jaw portion 16, which is outstanding on that side of arms 12, 14, away from the obtuse angle formed between the arm 55 portions. In the present instance, the grapple

is formed of wire and I have found that the simplest manner of bending the wire to produce the obtuse angle between members 12 and 14, is to form a convolute pivot eye 18, for a purpose later to be described.

A second jaw member comprises a bow-shaped bight 20 positioned in opposition to bight 16 and having merged therewith at each end of the curved portion an upstanding leg 22, the upper end of which is bent inward to form trunnions, as 24, that in the assembled device, pass through the pivot eyes 18, to permit relative swinging movement of the arms and the jaws in the manner suggested by the dotted line showing of Fig. 2. It is to be noted that arm portions 22 are slightly longer than arm portions 14, whereby the latter may, in closing about an object, swing past the arms 22, as shown in Fig. 2.

It is also to be noted that when the jaw portions 16 and 20 are closed about a jar or the like, the two arms 14 and 22 are disposed wholly to one side of a vertical plane A—A, drawn through the pivotal connection of members 18 and 24, as shown in Fig. 2.

It should not be overlooked that in this instance the plane A—A does not coincide with the vertical axis of the object to be gripped, nor the axis of the space enclosed between jaw portions 16 and 20, which axis coincides substantially with that designated B—B in which lies the handle 10.

By the reason of the arrangement that has been described, when a person uses my grapple, the grapple and the object being gripped will suspend from a person's fingers, as he grasps the handle 10, and the object will hang substantially upright therebelow. In this instance, the pivot lies on the side of the handle opposite jaw portion 16. By reason of this action, the crossing over of the arm portion 14 with respect to the arm 22 is maintained.

To remove the grapple from about a jar or other object, all that an operator need do is to swing the handle 10 from the solid line position of Fig. 2 toward that indicated by the dotted line showing, whereupon jaw portion 16 swings away from the object, and the jaws will open sufficiently to permit disengagement therefrom. Since the arm 22 and the jaw 20 are free to swing, activated largely by gravity when the jaws are open, the grapple is usually moved in the direction in which jaw 20 is positioned and the whole device will come free of the object.

While I have shown and described particular embodiments of my invention, it will occur to those skilled in the art that various changes and modifications may be made without departing from the invention, and I therefore aim in the appended claims to cover all such changes and modifications as fall within the true spirit and scope of my invention.

Having thus described my invention, I claim:

1. A bottle carrier, comprising: a first member including a bowed portion forming a first jaw merging at each end with an upstanding arm, each of said arms being in the form of a bell-crank directed to that side away from the mouth of said bowed portion and a pivot element at the apex thereof, said arms merging above said pivot elements into a handle, a second member including a bowed portion forming a second jaw, said second member being associated with said

first member so that the jaws are in opposition and said second member having an arm upstanding at each end of the bowed portion, each arm including a pivot element co-operable with the pivot element of the adjacent leg of the first member, the sides of the first jaw being of a length to pass the arms of the second jaw so that when a bottle is being gripped said arms diverge as the jaws close, said structure being arranged so that a vertical plane, including the handle and the center of gravity of the load carried by said jaws, excludes said pivot elements.

2. A bottle carrier, comprising: a first member including a bowed portion forming a first jaw merging at each end with an upstanding arm, each of said arms being in the form of a bell-crank and having an obtuse angle to that side away from the mouth of said bowed portion and means forming a pivot eye at the apex of the angle, said arms merging above said pivot eyes into a handle, a second member including a bowed portion forming a second jaw, said second member being associated with said first member so that the jaws are in opposition and said second member having an arm upstanding at each end of the bowed portion, each arm including a trunnion member mounted in the pivot eye of the adjacent arm of the first member, the sides of the first jaw being of a length to pass the arms of the second jaw so that when a bottle is being gripped said arms diverge as the jaws close, said structure being arranged so that a vertical plane, including the handle and the center of gravity of a load carried by said jaws, excludes said pivot eyes.

3. A bottle carrier, comprising: a first member formed of wire and including a bowed portion forming a first jaw merging at each end with an upstanding arm, each of said arms being in the form of a bell-crank and having an obtuse angle to that side away from the mouth of said bowed portion and a pivot convolute at the apex of the angle, said arms merging above said pivot convolutes into a handle, and a second member formed of wire and including a bowed portion forming a second jaw, said first and second members being associated together so that the jaws are in opposition, said second member having an arm upstanding at each end of the bowed portion, each arm including a trunnion mounted in the pivot convolute of the adjacent arm of the first member, the sides of the first jaw being of a length to pass the arms of the second jaw so that when a bottle is being gripped said arms diverge as the jaws close, said structure being arranged so that a vertical plane, including the handle and the center of gravity of a load carried by said jaws, excludes said pivot convolutes.
